RECEPTACLE AND CLOSURE THEREFOR

Herbert J. Moon, Clayton, Mo., assignor to National Enameling and Stamping Company, Milwaukee, Wis., a corporation of New Jersey

Application August 28, 1944, Serial No. 551,550

10 Claims. (Cl. 220—61)

1

The present invention relates to improvements in receptacles or containers, and more particularly to closure mechanisms for effecting a fluid-tight connection between the receptacle and the closure therefor.

Among the objects of the present invention is to provide a novel closure assembly for drums, barrels, or the like, characterized as including a contractible ring having means for contracting said ring to apply uniform pressure about the periphery of the closure and the drum or barrel so as to effect a fluid-tight connection therebetween.

The present invention more particularly comprehends a novel clamping mechanism including a contractible ring and means for contracting the same which is characterized as being operable in a plurality of angular positions with respect to the closure to facilitate operation of the ring structure.

The present invention has as a novel concept the idea of providing ring contracting means adapted to be operated either in substantially the plane of the closure or, more preferably, at an angle substantially ninety degrees therefrom whereby the ring can be manipulated with ease and without injury to the operator.

Another object of the present invention is to provide a ring contracting means as above described including adjustable means for varying the pressure applied by the ring to the container and closure therefor.

Still a further object of the present invention is to provide a ring contracting means including means engageable with the closure of the drum to facilitate contracting of the ring when the contracting means is disposed in substantially the plane of the closure and to prevent outward movement of the ring during such operation.

Other objects, features, capabilities and advantages are comprehended by the invention, as will later appear and as are inherently possessed thereby.

Referring to the drawings—

Figure 1 is a top plan view of a receptacle embodying novel closure mechanism made in accordance with the present invention;

Figure 2 is an enlarged fragmentary view similar to Figure 1 disclosing the closure mechanism more in detail;

Figure 3 is an enlarged fragmentary top plan view corresponding to the view of Figure 2 of the drawings, but disclosing the closing mechanism in a position for effectively contracting the ring of the assembly;

2

Figure 4 is a view taken in the plane represented by line 4—4 of Figure 3 of the drawings and showing the mechanism in closed position;

Figure 5 is a view similar to Figure 4 of the drawings showing the closure mechanism in open position;

Figure 6 is an enlarged fragmentary view in cross section taken in the plane represented by line 6—6 of Figure 2 of the drawings;

Figure 7 is an enlarged fragmentary view in cross section taken in the plane represented by line 7—7 of Figure 2 of the drawings;

Figure 8 is an enlarged fragmentary view in cross section taken in the plane represented by line 8—8 of Figure 2 of the drawings; and

Figure 9 is an enlarged fragmentary view in cross section taken in the plane represented by line 9—9 of Figure 2 of the drawings.

Referring now more in detail to the drawings, 20 an embodiment selected to illustrate the present invention is generally referred to as 2 and is shown in connection with a drum, barrel or other similar container 4 having a rolled or beaded edge 6 at the open end thereof which is closed by 25 a cupped closure member or head 8 having the upwardly and outwardly disposed marginal flange 10 adapted to embrace the rolled edge 6 of the container and to provide a fluid-tight connection between the closure member and the container. If desired, an annular gasket of 30 resilient material 12 may be introduced between the rolled marginal edge 6 and the flange 10 to assure a tight connection between these two elements at all times.

35 The closure mechanism to which this invention is directed comprises a channel-shaped ring 14 split as at 16 to provide a contractible ring structure adapted to engage the flange 10 of the closure member and the rolled marginal end 6 of the receptacle to draw the same into firm engagement when the ring is contracted by mechanism to be hereinafter more fully set forth.

Such mechanism is mounted in association 45 with the ring 14 through the medium of the inwardly disposed brackets 18 and 20 connected adjacent the free ends of the ring 14 as by means of welding or the like 22. The bracket 18 is formed with an inner rolled marginal edge adapted to provide a bearing 24 for a pin 26 rotatably mounted therein and to which, as by 50 welding material 28, is connected a clevice 30. Pivotally mounted in the clevice 30 by means of the pin 32 is an operating lever 34 disposed between the two bearing elements 36 and 38. As 55 clearly shown in the drawings, the lever 34 is of

arcuate shape to conform to the interior contour of the upstanding flange 10 of the closure member 8 and is provided with an offset handle 40 adapted to be gripped by an operator for moving the same.

The bracket 20 likewise is formed with its inner edge rolled to provide journal bearings 42 and 44, adapted to rotatably receive a threaded eye bolt 46 which is adjustably positioned therein through the medium of a nut 48 threadedly engaging the shank of said eye bolt. The bearing 44 is internally threaded to engage the threads of the bolt 46, while the bore of bearing 42 is smooth and of such a size as to receive the threaded end of the bolt 46. The eye bolt 46 is formed with the eye 50 adapted to provide a pivotal connection through the medium of the pin 52 for the oppositely disposed link elements 54 and 56 which are connected to the pin 52 adjacent one of the ends thereof. As noted in the drawings, the link elements 54 and 56 are of arcuate formation to clear the bracket 18 and the connection for the lever thereto and have their outer ends pivotally secured to the lever 34 by means of the pin 58.

The link and lever assembly is operable to contract the ring 42 about the periphery of the drum and closure member as above described. The ring may be moved into opposed relation to the beaded edge 6 of the drum and the flange 10 with the link and lever mechanism annularly disposed with respect thereto, as clearly shown in Figure 3 of the drawings. The lever can be readily grasped by the operator when in that position and the same moved until the ring is in tight engagement with the drum and closure mechanism, as shown in full lines in Figure 3 of the drawings. After this has been effected, the link and lever mechanism, through the pivotal connections 46 and 26, respectively, may be moved downwardly into substantially the plane of the closure 8 and the lever moved into locked engagement with the bracket 6, as clearly shown in Figure 9 of the drawings. When in this position, the pin 62 may be inserted within the aligned openings provided in the bracket 60 and lever 34 for holding the clamping mechanism in operative position.

When it is desired to remove the closure member 8 from the drum 4, the lever 34 may be released from its engagement with bracket 60, after which the same may be moved into a position as shown in Figure 3 and pressure released therefrom to allow the ring 14 to expand.

In order to facilitate the contracting of the ring 14 in the event the operator desires to do so when the lever 34 is in substantially the plane of the cover, the lug 64 is provided and is secured in depending relation to the bracket 18 in a position to engage the upstanding flange 10 of the closure member and to prevent outward movement of the ends of the contractible ring when pressure is applied to the lever 34 to contract the ring. It is to be noted that when the lever 34 is finally moved into closed position, the lug 64 does not engage or in any way touch the upstanding flange 10 of the closure member.

With the above structure, particularly characterized as involving the use of ring contracting mechanism which may be moved into various angular positions with respect to the plane of the closure member, it is possible to readily and easily contract the ring without injury to the operator, which is one of the undesirable features of such mechanism where the lever 34 must be operated in substantially the plane of the cover.

While I have herein described and upon the

drawings shown an illustrative embodiment of the invention, it is to be understood that the invention is not limited thereto but may comprehend other constructions, arrangements of parts, details and features without departing from the spirit of the invention.

What is claimed is:

1. A device for removably securing a head on a receptacle, comprising a contractible channeled ring for pressing the head and receptacle together when the ring is contracted, and means for contracting said ring in a plurality of angular positions with respect to said head, said means having pivotal connections with rotatable members adjacent the ends of said ring, said members being rotatable about a common axis lying substantially in the plane of said ring whereby said means can be swung about said pivotal connections.

2. A device for removably securing a head on a receptacle, comprising a contractible channeled ring for pressing the head and receptacle together when the ring is contracted, and a link and lever assembly each pivotally connected adjacent one end of said ring to a member rotatable with respect to said ring, said members being rotatable about a common axis lying substantially in the plane of said ring whereby said link and lever assembly is adapted to contract said ring in a plurality of angular positions with respect to said head.

3. A device for removably securing a head on a receptacle, comprising a contractible channeled ring for pressing the head and receptacle together when the ring is contracted, a link and lever assembly each pivotally connected adjacent one end of said ring to a member rotatable with respect to said ring, said members being rotatable about a common axis lying substantially in the plane of said ring whereby said link and lever assembly is adapted to contract said ring in a plurality of angular positions with respect to said head, and means for adjusting one of said members for varying the contraction of said ring.

4. A device for removably securing a head on a receptacle, comprising a contractible channeled ring for pressing the head and receptacle together when the ring is contracted, a link and lever assembly each pivotally connected adjacent one end of said ring to a member rotatable with respect to said ring, said members being rotatable about a common axis lying substantially in the plane of said ring whereby said link and lever assembly is adapted to contract said ring in a plurality of angular positions with respect to said head, and means extending inwardly and downwardly from one end of said ring and adapted to engage with said head to prevent outward movement of the ring when contracted by said assembly in certain of its angular positions.

5. A device for removably securing a head on a receptacle, comprising a contractible channeled ring for pressing the head and receptacle together when the ring is contracted, said ring having inwardly extending brackets disposed adjacent the ends thereof, and a link and lever assembly pivotally connected to a member rotatable in each of said brackets, said members being rotatable about a common axis lying substantially in the plane of said ring whereby said link and lever assembly is adapted to contract said ring in a plurality of angular positions with respect to said head.

6. A device for removably securing a head on a receptacle, comprising a contractible channeled ring for pressing the head and receptacle to-

gether when the ring is contracted, said ring having inwardly extending brackets, each having a bearing formed therein, an adjustable rod rotatably mounted in one of said bearings, a pin rotatably mounted in the other of said bearings to rotate about an axis which is common to both the pin and the rod and which lies substantially in the plane of said ring, a lever pivotally connected to said pin, and a link pivotally connected to said lever and to said rod whereby said ring can be contracted by said lever and link assembly when in a plurality of angular positions with respect to said head.

7. A device for removably securing a head on a receptacle, comprising a contractible channeled ring for pressing the head and receptacle together when the ring is contracted, said ring having inwardly extending brackets, each having a bearing formed therein, an adjustable rod rotatably mounted in one of said bearings, a pin rotatably mounted in the other of said bearings to rotate about an axis which is common to both the pin and the rod and which lies substantially in the plane of said ring, a lever pivotally connected to said pin, a link pivotally connected to said lever and to said rod whereby said ring can be contracted by said lever and link assembly when in a plurality of angular positions with respect to said head, and a lug carried by one of said brackets adapted to engage said head to prevent outward movement of the ring with respect to said head when contracted by said lever and link in certain of its angular positions.

8. A device for removably securing a head on a receptacle, comprising a contractible channeled ring for pressing the head and receptacle together when the ring is contracted, said ring having inwardly extending brackets, each having a bearing formed therein, a threaded rod rotatably mounted in one of said bearings, a nut on said rod adapted to adjust the same axially with respect to said bearing, a pin rotatably mounted in the other of said bearings to rotate about an axis which is common to both the pin and the rod and which lies substantially in the plane of said ring, a lever pivotally connected to said pin, and a pair of links pivotally connected to said lever and to said rod whereby said ring can be contracted by said lever and link assembly when in a plurality of angular positions with respect to said head.

9. A device for removably securing a head on a receptacle, comprising a ring for pressing the head and receptacle together, said ring having inwardly extending brackets, each having a bearing formed therein, an adjustable rod rotatably mounted in one of said bearings, a pin rotatably mounted in the other of said bearings to rotate about an axis which is common to both the pin and the rod and which lies substantially in the plane of said ring, a lever pivotally connected to said pin, and a link pivotally connected to said lever and to said rod whereby said ring can be moved by said lever and link assembly when in a plurality of angular positions with respect to said head.
10. A device for removably securing a head on a receptacle, comprising a ring for pressing the head and receptacle together, said ring having inwardly extending brackets, each having a bearing formed therein, a threaded rod rotatably mounted in one of said bearings, a nut on said rod adapted to adjust the same axially with respect to said bearing, a pin rotatably mounted in the other of said bearings to rotate about an axis which is common to both the pin and the rod and which lies substantially in the plane of said ring, a lever pivotally connected to said pin, and a pair of links pivotally connected to said lever and to said rod whereby said ring can be moved by said lever and link assembly when in a plurality of angular positions with respect to said head.
